CLAIM

The ornamental design for a TV set, as shown and described.

DESCRIPTION

FIG. 1 is a front perspective view of a TV set, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 2; and,

FIG. 11 is an enlarged view of the encircled portion 11 in FIG. 6.

The broken lines illustrating portions of the TV set form no part of the claimed design.

The dot-dashed broken lines define boundaries of the claimed design and form no part the claimed design.

The dot-dot-dash broken lines encircling portions of the claimed design that are illustrated in enlargements form no part of the claimed design.
